No. 738,686.

PATENTED SEPT. 8, 1903.

W. E. JOHNSON.
NON-REFILLABLE BOTTLE.
APPLICATION FILED JAN. 10, 1903.

NO MODEL.

UNITED STATES PATENT OFFICE.

WILLIAM E. JOHNSON, OF SPOKANE, WASHINGTON, ASSIGNOR OF ONE-HALF TO SAMUEL L. THOMAS, OF HATTON, WASHINGTON.

NON-REFILLABLE BOTTLE.

SPECIFICATION forming part of Letters Patent No. 738,686, dated September 8, 1903.

Application filed January 10, 1903. Serial No. 138,513. (No model.)

To all whom it may concern:

Be it known that I, WILLIAM E. JOHNSON, a citizen of the United States, and a resident of Spokane, in the county of Spokane and State of Washington, have made certain new and useful Improvements in Non-Refillable Bottles, of which the following is a specification.

It is the object of my invention to effect an improvement in that class of non-refillable bottles which are provided with a stopper or plug having a valve adapted to open for discharge of contents of bottle when the latter is held in the required position.

The details of construction, arrangement, and combination of parts are as hereinafter described, and particularly specified in the claims.

In the accompanying drawings, Figure 1 is a central longitudinal section of a bottle-neck 20 provided with my improved valve attachment or stopper. Fig. 2 is a perspective view of the valve attachment or stopper detached. Fig. 3 is a central longitudinal section of a portion of the bottle-neck and the valved stopper 25 therein, the same being shown in the position required to effect discharge of liquid. Fig. 4 is a horizontal section on the line 4-4 of Fig. 1. Fig. 5 is a perspective view of the latch-collar or ring forming an attachment of the stopper 30 and serving to lock the latter in place. Fig. 6 is a cross-section of the device shown in Fig. 5. Fig. 7 is an edge view of the valve-seat with valve attached. Fig. 8 is a perspective view of portions of the gaskets or packing applied to the valve of the stopper.

In Figs. 1 and 2, A indicates the bottle-neck, and B the plug or stopper inserted in the neck, the same being shown detached in Fig. 2. The bottle-neck is slightly tapered or narrowed from the top downward, and near its upper end it is provided with an internal shoulder 1, with which latches or locking devices hereinafter described engage, so as to hold the stopper in place. The latter consists 45 mainly of an upper cylindrical chambered portion 2, a lower cylindrical chambered portion 3, and a connecting-tube 4, which has a zig-zag form. The upper chamber 2 is provided exteriorly with a recess or groove 5 to adapt 50 it for reception of a metallic ring 6. (See Fig. 5.) This ring is in turn provided with gravity

latches or catches 7, the same being pivoted to the sides of the ring 6, as illustrated in Figs. 5 and 6. The upper ends of these latches being enlarged, they tend to fall outward automatically, and thus engage the shoulder 1 of the bottle-neck A when the stopper B is inserted. The ring 6 may be divided transversely and its ends lapped and secured or it may be constricted in any other manner 55 which will adapt it for attachment to the stopper B. It may be constructed of flexible or spring metal and preferably seated upon elastic packing 7^a, preferably cork, which will be compressed somewhat in the operation of 60 securing together the lapped ends of the ring 6.

The open chamber 2 of the stopper B is extended above the groove in which the locking-ring 6 is arranged and is also extended laterally, as shown in Fig. 1, so as to come in contact with the portion of the neck A which is exterior to the shoulder 1. Thus such extension, which is indicated by 2^a, Fig. 1, serves as a guard preventing the introduction of any tool or device into contact with the 75 latches 7. It is therefore impossible to so manipulate the latter as to effect surreptitious detachment of the stopper. The lower chamber 3 of the stopper B contains the valve-seat 8 and valve 9. As shown in Figs. 1, 3, and 80 4, the valve-seat 8 is annular in form and provided in its upper edge and inner side with a rabbet or groove 10 (see Fig. 3) to provide for duly seating the rim of the valve 9. A rubber gasket or packing 11 (see Fig. 8) is 85 duly secured in the rabbet 10 of the valve-seat and provided with a semicircular groove or depression 12. A corresponding gasket or packing 11^a (see Fig. 8) is applied to the under side of the valve 9 and provided with a 90 semicircular projection 12^a on its under side. It will be seen that when the valve is closed the rib or projection 12^a of the packing 11^a fits in the groove 12 of the lower packing 11, and thus forms liquid-tight seal. The valve 95 9 is enlarged at the center, and thereby weighted. To assist gravity in holding the valve duly seated, I apply a coil-spring 13, (see Figs. 1 and 7,) the same being coiled about the pivot of the valve-hinge and its respective ends bearing against the valve-seat 8 and edge of the valve, as shown in Fig. 1.

The valve-seat 8 is held in place in the stopper-chamber 3, a packing 14 of cork or other suitable material being applied between it and the inner sides of the chamber, as shown in Fig. 1. The said packing is constructed in such manner as to lap around the lower edge of the chamber 3, and thus interposed between it and the bottle-neck. The valve-seat may be cemented in place as well as the packing, but ordinarily friction alone may suffice. I propose to construct the entire stopper B of glass or metal; but it is to be understood that any other suitable material may be employed. The zigzag tube 4 is bent at two sharp or acute angles, so that it is utterly impracticable to insert any device through it, and thereby tamper with the valve 9. In other words, surreptitious access to the valve is entirely cut off by the form and arrangement of the tube. In practical construction of the stopper B it is preferably made integral; but I do not propose in all cases to restrict myself to this construction, since it is practicable to make the tube B in sections and also to make it detachable from the upper and lower chambers 2 and 3. In case the tube 4 be made of glass it will require to be bent into the form shown while still in a plastic state from the effect of heat. If made of a duly flexible or ductile metal, it may be formed straight in the first instance and then bent while cold. In brief, I do not restrict myself to any particular mode of construction of this portion of the device, since various ones are practicable.

It will be seen that when the bottle has been filled with liquid up to the neck the stopper B is easily inserted by simply pressing it down into the neck until its latches automatically engage the shoulder 1, as in Fig. 1. It will be understood that in this operation the outer portion of the packing 14 will be firmly compressed between the neck A and the stopper-chamber 3, so that the passage of liquid at that point will be effectually and permanently cut off. A cork 15 is then inserted, the same being made of such form as to enter the chamber 2 of the stopper B and also fill the upper portion or end of the bottle-neck A, as shown. Thus the contents of the bottle will be effectually sealed, and when it is desired to remove any portion of the same, the cork 15 having been detached, the bottle is inclined, as shown in Fig. 3, in which case the force of gravity acting on the weighted valve is added to the weight of the liquid and the two are sufficient to unseat the valve, as shown. As soon as the liquid begins to run from the bottle, a partial vacuum is necessarily formed therein, and thus it sometimes results in causing the valve to reseat, so as to prevent further escape of the liquid; but ordinarily this will not occur, since by the provision of the chamber 3 in the stopper B a considerable volume of air is present and enters the bottle to supply the vacuum created by the escape of the liquid. It will be understood that when the bottle is held in

the position required and gravity and the pressure of the liquid overcome the tension of the spring the inertia of the weight of the valve is such as to prevent its returning to its seat so long as a vacuum of only slight tension is created. When the bottle is returned to a horizontal position or, better still, to the vertical, the conditions are changed so that the spring effects the closure of the valve upon its seat. Thus it is impossible to refill the bottle by immersing it in a liquid and holding it in horizontal position.

It is desirable for the sake of economy that the stopper B with its attachment shall be preserved after the contents of the bottle have been discharged, and for this purpose it is necessary that the bottle-neck may be safely and easily broken to allow removal of the stopper. For this purpose I provide the bottle-neck with a circumferential groove 16, (see Fig. 1,) the same being preferably located directly opposite the shoulder 1. This groove furnishes a track for a glass-cutting tool or it weakens the neck at that point, so that a light blow upon the exterior portion of the neck will effect a breakage and detachment of the shouldered portion. The stopper with its attachments being removed by the retailer or consumer may be returned to the manufacturer or jobber for reuse.

Having thus described my invention, what I claim as new, and desire to secure by Letters Patent, is—

1. The combination, with a bottle-neck provided with an interior shoulder, of a stopper having a valve in its lower portion, and a zigzag tube above said valve, and means for engaging the aforesaid shoulder, substantially shown and described.

2. The combination, with a bottle-neck having an interior shoulder, of a valved stopper, a chamber or enlarged upper portion having circumferential groove, and a ring held in said groove and provided with pivoted gravity-latches for engaging the aforesaid shoulder, substantially as shown and described.

3. The combination, with a bottle-neck having an internal shoulder, of the valved stopper having an enlarged upper portion, and a metal ring secured to the latter and provided with devices for engaging said shoulder, substantially as shown and described.

4. The combination, with a bottle-neck having an internal shoulder, of a valved stopper, a ring applied to the upper portion of the stopper, and provided with latches for engaging the said shoulder, the stopper having an extension above the ring which projects laterally so as to contact with the portion of the bottle-neck above the shoulder and thereby serve as a guard for the latches, substantially as shown and described.

5. The combination, with the bottle-neck having an internal shoulder, of a stopper provided at its lower end with a valve and at its

upper end with means for automatically engaging said shoulder and also with an upper open chamber, and a sealing-cork adapted for insertion in the said chamber and the mouth of the bottle-neck, substantially as shown and described.

6. The combination, with the bottle-neck, having an internal shoulder, and a stopper provided with means for automatically engaging said shoulder, and holding the stopper permanently in place, of a weighted flap-valve, and a valve-seat held in the lower portion of the stopper, and a coil-spring applied to the hinge of the valve and adapted to hold the same normally seated, substantially as shown and described.

7. The combination, with the bottle-neck, and the stopper adapted to be locked therein, and provided at its lower end with a chambered portion, of a valve-seat which is rabbeded on its upper side and provided with packing, and a weighted valve provided with corresponding packing, and a coil-spring adapted for holding the valve normally seated, substantially as shown and described.

8. The combination, with a bottle-neck, having an internal shoulder and tapered toward its lower end, of a stopper adapted to be locked with the same and having a weighted valve attached, and packing applied between such seat and the stopper-chamber and extending around the lower edge of the latter

and interposed between it and the bottle-neck, substantially as shown and described.

9. The improved stopper comprising an upper chambered portion, a lower chambered portion, and an intermediate connecting-tube having a zigzag form, the said parts being constructed integral, substantially as specified.

10. The improved stopper comprising an upper portion adapted for attachment of locking devices, a lower portion adapted for attachment of a valve, and the intermediate portion consisting of a zigzag tube, substantially as shown and described.

11. The improved stopper for non-refillable bottles the same comprising an upper portion having devices for locking the stopper in a bottle-neck, a lower portion having a valve adapted to normally seat itself as described, and a connecting-tube having an angular form as and for the purpose specified.

12. The combination of the valved stopper having latches at its upper end, with a bottle-neck having an internal shoulder with which said latches engage, and an exterior groove adjacent to the internal shoulder, as and for the purpose specified.

WILLIAM E. JOHNSON.
